UNITED STATES PATENT OFFICE

FRANK J. FREDA, OF DETROIT, MICHIGAN.

BUTTONHOLE ATTACHMENT FOR SEWING-MACHINES.

No. 808,914.

Specification of Letters Patent.

Patented Jan. 2, 1906.

Application filed December 27, 1904. Serial No. 238,378.

To all whom it may concern:

Be it known that I, FRANK J. FREDA, a citizen of the United States, residing at Detroit, in the county of Wayne and State of Michigan, have invented certain new and useful Improvements in Buttonholing Attachments for Sewing-Machines, of which the following is a specification, reference being had therein to the accompanying drawings.

10 It is the object of the invention to provide a simple construction of mechanism for operating a thread-guide in buttonholing-machines. With the type of machines to which my improvement is applied the needle-bar alternates between two paths of descent in a plane transverse to the feed, so as to form the buttonholing-stitch. To reinforce the buttonhole, it is advantageous to employ a gimp which is embraced and covered by the stitches 20 of the machine, and to further reinforce the inner edge of the buttonhole a second thread is looped about the stitches, said thread being carried by the thread-guide above referred to.

25 In the drawings, Figure 1 is a perspective view of a portion of the sewing-machine to which my improvement is applied. Fig. 2 is a rear elevation of a portion of my improvement, showing both positions of the guide.

30 A is the reciprocating needle-bar, which is secured in bearings in the head B and is operated by mechanism (not shown) for alternating its path of descent, as indicated by full and dotted lines. C is the thread engaging the needle D, carried by said bar, and E is the thread-guide for the reinforcing-thread.

35 To produce the desired stitch, it is necessary that the guide E should be shifted alternately upon opposite sides of the needle-bar and with its thread-delivering end in advance of the needle—*i. e.*, beyond the same in the direction of feed of the work. It is also necessary that this guide be shifted when the 45 needle-bar is down, thereby necessitating a curved path of movement. This movement is produced by mechanism of the following construction:

40 F is a reciprocating bar which extends horizontally of the machine and is operated at one end by any suitable mechanism. (Not shown.) The timing of the mechanism is such as to produce one complete reciprocation of the bar F for each alternate reciprocation of the needle-bar.

45 G is a lever pivotally secured at H to the

head B of the machine and pivotally connected at I to the end of the bar F. This lever is formed in two sections, and the lower section J thereof is pivotally connected at K 60 to the upper section, so as to swing in a plane transverse to the plane of movement of the lever as a whole.

L is an antifriction-roll secured to the lower end of the member J, and M is a slotted cam 65 secured to the side of the head B and engaging the roll L. The shape of this cam is substantially as illustrated, the slot inclining outward from opposite sides of the center a, so as to produce an angular or substantially 70 segmental path of movement of the roll L in a horizontal plane.

N is an arm secured to the member J and projecting outward and downward therefrom. The thread-guide E is secured to the 75 lower end of this arm N, and by reason of the movement imparted to the member J by the cam M said thread-guide is shifted through a segmental path. To form the desired stitch, it is necessary that the thread in the guide E 80 be drawn, and this is accomplished also by the arm N in coöperation with stationary thread-guides O on the head B.

In operation the reciprocation of the bar F shifts the guide E through a segmental 85 path to be upon opposite sides of the needle-bar during alternate operations thereof. This will hold the thread fed from the guide E in proper position for forming the loop, and during the shifting movement of the 90 guide the thread will be arranged to be drawn in, which forms the reinforcement for the inner edge of the buttonhole.

What I claim as my invention is—

1. In a buttonholing-machine, the combination with a reciprocating needle-bar, of a thread-guide shiftable through a segmental path, to be alternately upon opposite sides of said needle-bar and mechanism for shifting said guide, comprising a vertically-arranged 100 lever mounted on a stationary pivot, said lever having its lower end universally movable in a horizontal plane, a connection between the lower end of said lever and the thread-guide, means for reciprocating said lever and means for guiding the lower end thereof in an 105 angular course.

2. In a buttonholing-machine, the combination with a reciprocating needle-bar, of a thread-guide shiftable through a segmental path, to be alternately upon opposite sides of said needle-bar and mechanism for shifting 110

said guide comprising a vertically-arranged lever, formed in two sections, the lower section being pivoted to the upper section to swing in a plane transverse to the plane of movement of the lever as a whole, means for reciprocating said lever connected to the upper section thereof, a connection between the lower section of said lever and the thread-guide, and means for guiding the lower end of said lever through an angular course.

3. In a buttonholing-machine, the combination with a reciprocatory needle-bar, of a thread-guide shiftable through a segmental path, to be alternately upon opposite sides of said needle-bar and mechanism for shifting

said guide, comprising the reciprocatory rod F, the lever G to which said rod is attached, the lower section J of said lever, pivoted to the upper section to swing in a transverse plane, the arm N connecting the section J with said thread-guide, the slotted guide-plate M and the antifriction-roll L on the section J for engaging the slot in said guide-plate. 20

In testimony whereof I affix my signature in presence of two witnesses.

FRANK J. FREDA.
